UNITED STATES PATENT OFFICE.

JOSEPH M. CONLEY, OF DETROIT, MICHIGAN, ASSIGNOR OF ONE-HALF TO A. M. BIRD, OF MEGANTIC, CANADA.

SIGNAL-FLAG SUPPORT.

Application filed August 1, 1922. Serial No. 579,054.

To all whom it may concern:

Be it known that I, JOSEPH M. CONLEY, a citizen of the United States, residing at Detroit, in the county of Wayne and State 5 of Michigan, have invented certain new and useful Improvements in Signal-Flag Supports, of which the following is a specification.

This invention has reference to signal flag supports for use on railroads and its object 10 is to provide a support in which the flag, when not in use, may be protected from the effects of weather or other damaging conditions, and in which the flag may be extended into operative position for use without liability of damage or displacement.

The invention is of a nature which permits the flag to be set for either the housed or exposed position at will with no material 20 effort and to hold either position against accidental displacement.

In accordance with the invention, there is provided a yoke structure adapted to be engaged behind the customary fish plate, with 25 the yoke structure of V-shape with the apex of the yoke elastic to hold the wide end of the yoke in engagement with the fish plate, and a mast is erected at the apex end of the yoke which mast carries a casing for hous- 30 ing and protecting the signal flag, permitting the latter to be hidden from view or displayed as the case may be, and provision is made for holding the mast in an erect position or laid down.

The invention will be best understood 35 from a consideration of the following detailed description taken in connection with the accompanying drawing forming a part of the specification, with the understanding 40 that the invention is not confined to any exact conformity with the showing of the drawing, but may be changed and modified, so long as such changes and modifications mark no material departure from the salient 45 features of the invention as expressed in the appended claims.

In the drawings,

Figure 1 is a perspective view of a signal flag support embodying the invention, 50 Fig. 2 is a plan view with some parts in section of the yoke portion of the device,

Fig. 3 is a section on the line 3—3 of Fig. 2,

Fig. 4 is a section on the line 4—4 of Fig. 1,

Fig. 5 is a detailed view of the flag holder,

Fig. 6 is a section on the line 6—6 of Fig. 5 with the parts collapsed.

Referring to the drawings, there is shown a railroad track of customary construction 60 including rails 1 and showing fish plates 2.

Adapted to be locked to the rail by one of the fish plates is a yoke of substantially V-shape, made up of two angle irons 3, 4, respectively, each having at one end a lip 5 65 shaped to be introduced between the fish plate 2 and the adjacent portion of the rail.

Each member 3 and 4 terminates at the end remote from the lip 5 in an extension 6, the extensions substantially parallel one 70 with the other and the basic webs of the two members 3 and 4 are joined by a connector 7 which may be conveniently formed of strap material. The legs 3 and 4 of the yoke are joined to the connector 7 by pivots 8 so 75 that the width of the basic end of the yoke may be varied at will to permit the introduction of the lip 5 between the ends of the fish plate and the adjacent track.

The extensions 6 are connected by a bolt 80 9 traversing the upright webs of the members 3 and 4 at the ends remote from the track, and the bolt 9 at opposite sides of the upright web of the member 4 carries spaced nuts 10, 11, one of which may be employed 85 as a lock nut. The bolt 9 also carries between the upright web of the two members 3 and 4 a spring 12 capable of being compressed by the approach of the extensions 6 of the members 3 and 4.

Carried by the strap 7 and connected thereto by rivets 14 is an arc 15 through which the pivot 13 extends, whereby a flag pole 16 is made fast to the arc 15 and the strap 7, so as to turn about the pivot 13 permitting the flag pole to be laid down in a substantially horizontal position or raised to an upright position, these two positions being determined by a sildable bolt 17 engaging in notches 18 in the segment 15.

At the top of the flag pole 16, there is secured a cylindrical casing 19 inclosing a

roller 20 on which is made fast the flag 21 and in order to wind or unwind this flag, the roller is provided with a crank 22 at one end.

5 At the end of the casing 19 remote from the crank 22, there is secured a hook 23 designed to carry a lantern 24 or other light giving element.

Fast to the casing 19 midway of its length 10 is another sleeve 23^a held in position on the upper end of the mast 16 by a thumb screw 24, while fast to a rod 25 at the lower end of the flag 21 is a sleeve 26 capable of sliding along the mast 16 to be held thereto in adjusted position by a thumb screw 27.

When it is desired to display the flag 21, the latter is withdrawn from within the casing 19 by unwinding said flag from the roller 20, the sleeve 26 then sliding along the 20 mast 16 to the desired position where the sleeve 26 is secured to the mast by the thumb screw 27.

In order to protect the flag 21 from the effects of weather, the casing 19 is provided 25 with a slot 27' having a protecting lip 28 through which the flag may be drawn.

When the yoke made up of the members 3 and 4 is clamped in place by the fish plates 2, the mast 16 may be raised so as to be fixed 30 in an upright position as indicated in Figure 1. The flag may then be displayed by drawing it from the casing 19 and locking the rod 25 against retraction the mast 16 being held in the upright position by the engagement 35 of the latch bolt 17 in the upright notch 18.

When it is desired to retract the flag and to drop the mast 16, the latch bolt 17 is withdrawn from the upright notch 18, and the mast is dropped until engaged in the low- 40 ered position with the flag retracted.

The invention has the advantage of being capable of manufacture in most part from standard materials, readily assembled and therefore cheaply manufactured and capable 45 of being installed at low cost wherever desired, along a railroad without the necessity

of any change in such railroad and wherever fish plates are available, such devices occurring at frequent intervals.

The mast 16 is made oblong in cross-section, so that it must of necessity be placed in one position only with relation to the track, bringing the flag, when upright always in proper position with relation to the track. The mast structure is such as to collapse as compactly as possible.

What is claimed is:—

1. A signal flag support for railways, comprising a yoke having one end adapted to engage a fish plate of a railroad track and the other end of the yoke having pivoted thereto a mast capable of being moved from a substantially horizontal to an upright position, and a flag and a casing therefor with the flag retractable into the casing and provided with means for locking the flag in the projected position.

2. A signal flag support for railways comprising a base member having means for securing it to a fish plate of a railroad, a mast pivoted to the base member and having means for holding it in an upright or a horizontal position, a flag, and a casing therefor carried by the mast, with the flag movable into and out of the casing when the mast is in the upright position.

3. A signal flag support comprising a base member with means for attaching it to a track rail to project it to one side thereof, a mast carried by the base member in fixed relation to the track and pivotally mounted to move from a substantially horizontal to an upright position, a casing fast to the mast, a roller within the casing, a flag carried by the roller and movable into and out of said casing, and means associated with the flag and the mast co-operating to hold the flag in either the retracted or extended position.

In testimony whereof, I affix my signature hereto.

JOSEPH M. CONLEY.
